BREATHER TYPE STORAGE APPARATUS
FOR GASES AND VOLATILE LIQUIDS

John H. Wiggins, Chicago, Ill.

Application March 15, 1941, Serial No. 383,525

10 Claims. (Cl. 220—85)

This invention relates to tanks and containers that are used for storing gases and/or volatile liquids, and particularly storage apparatus of the kind that are equipped with a breather type roof or balloon roof, which is adapted to flex or move vertically so as to vary the internal volume of the container.

One object of my invention is to provide a storage apparatus of the general type mentioned, whose roof is constructed in a novel manner that greatly decreases the amount of rain water that can possibly collect on the roof, if the drainage system of the roof becomes clogged, or even if the roof is not provided with a drainage system.

Another object is to provide a storage apparatus of the general type mentioned provided with a roof whose top area is made up of steeply pitched or sharply sloped drain surfaces, that lead to a water collection trough located relatively close to the peripheral edge of the roof.

Another object is to provide a breather type or balloon type roof for storage tanks and containers, which is of such design or construction that the flexible portion or portions of the roof, while passing from a downwardly inclined into an upwardly inclined position, or vice versa, will move through a horizontal plane, noiselessly and with a minimum of wrinkling of the roof plates.

Another object is to provide a breather or balloon type roof for storage tanks and containers, which is constructed in a novel manner that greatly decreases the amount of steel required for the supporting structure that sustains the roof when it is in its downwardly flexed or extreme depressed position.

Another object is to provide a tank roof of the general kind above mentioned, that can be properly supported in its downwardly flexed condition, by a roof supporting structure that is of considerably less area than the roof supporting structures used with breather and balloon type roofs of conventional design.

And still another object of my invention is to increase the capacity of storage apparatus of the kind and type above referred to, without adding to the cost of building or erecting the apparatus.

Briefly described, the tank roof that constitutes my present invention, is composed of a flexible, substantially washer-shaped peripheral portion having its outer edge attached in a gas-tight manner to the side wall of the tank and projecting inwardly from said side wall towards the center of the tank, a stiff, vertically-disposed tubular member, hereinafter referred to as a

5 "rim," attached in a gas-tight manner to the inner edge of said washer-shaped peripheral portion and projecting upwardly from same, and a central roof portion having its outer edge attached in a gas-tight manner to the top edge of said rim, said peripheral portion and central portion lying in different vertical planes, or, in other words, being disposed in such relationship that the peripheral portion surrounds the central portion or lies beyond or outside of the vertical zone in which said central portion is located. Said central roof portion may comprise or consist of a cone-shaped or convex-shaped part, it may comprise or consist of a flexible metal diaphragm, or it may be composed of a plurality of flexible metal members or parts joined together by one or more interposed collars or ring-shaped connecting devices that maintain said flexible parts in different planes. The rim previously referred to that joins the inner edge of the flexible peripheral portion of the roof to the central or center portion of the roof, is preferably constructed in the form of a stiff, tubular-shaped, vertically-disposed member that may be cylindrical-shaped, polygonal-shaped or any other preferred shape in cross section. It cooperates with the flexible peripheral portion of the roof, when the roof is flexed downwardly to form a water collection trough that is preferably equipped with one or more drains. The flexible peripheral portion, in general shape or form, resembles a washer or flat annulus that is disposed at approximately right angles to the side wall of the tank and to the rim with which it co-acts to form a water collection trough, as above explained, the said rim constituting a vertical side wall for said trough and the said flexible peripheral portion constituting an inclined bottom for said trough.

40 The central portion of the roof, the flexible peripheral portion, and the interposed rim that joins said two portions together, are preferably so proportioned and combined that when the roof is in its extreme downwardly flexed position, the outer edge of the central portion of the roof attached to said rim, will lie in a horizontal plane coincident with or higher than the horizontal plane in which the top edge of the tank side wall lies. Accordingly, no matter how 45 much water may collect on the flexible peripheral portion of the roof, said collected water cannot rise high enough to flow over the top edge of said rim, onto the central portion of the roof. In the preferred form of my invention, the center portion of the roof is formed by a cone-

shaped or convexed part, which, in any and all positions of the roof, will be self-draining, or capable of shedding water quickly and efficiently from the same. Bearing in mind that said peripheral portion constitutes only a relatively small part of the total area of the roof and is so constructed or arranged that water which collects on said peripheral portion, even when the roof is in its extreme downwardly flexed position, cannot back up onto the central portion of the roof, it will be seen that the weight of an excessive or abnormal rain load does not have to be taken into consideration in designing the supporting structure that sustains the roof when the roof is in its downwardly deflected position. In fact, I have demonstrated that the tank roof herein described can be properly sustained by a roof supporting structure formed by permanent frame members of such weight and area, that a saving of approximately 10% of the steel used in the roof and in the roof supporting structure is possible.

The central portion and the peripheral portion of the roof are constructed from metal plates joined together by gas and liquid-tight joints. One objectionable feature or characteristic of the conventional breather or balloon type roof is that wrinkles of perceptible size form in the roof plates, and the plates buckle, flex and make a considerable noise, while the roof is moving through a horizontal plane in passing from its extreme downwardly flexed position into its extreme upwardly flexed position, and vice versa. I have overcome the above mentioned objectionable characteristic of the conventional breather roof by dividing the area of the roof into a central zone of relatively great radius, joined by a relatively heavy, vertically-disposed rim to a peripheral zone of considerably less radius than the central zone, and imposing an eccentric load on said central zone. As the pressure in the gas space of the apparatus rises, the peripheral zone of the roof assumes an upwardly flexed condition, without wrinkling or making a noise, before the rim leaves or rises off of the roof supporting structure; and as the pressure continues to rise, the rim starts to move upwardly, but, on account of the eccentric load on the central zone, the rim assumes a slightly inclined or tilted position, with the result that the inner edge of the flexible peripheral portion of the roof is eased up through the horizontal plane, intermediate the two extreme flexed positions of said peripheral portion, substantially noiselessly and with a minimum of stresses, hereinafter more fully explained. Similarly, the inner edge of the flexible peripheral portion of the roof is eased down through the horizontal plane without wrinkling or producing a noise during the downward movement of the roof.

Figure 1 of the drawings is a fragmentary top plan view of my improved apparatus, with the roof broken away so as to show the roof supporting structure.

Figure 2 is a fragmentary, vertical transverse sectional view of the apparatus.

Figure 3 is a vertical transverse sectional view, illustrating another form of my invention, wherein the central portion of the roof is composed of two flexible parts joined together by an interposed, ring-shaped connecting member.

Figure 4 is a vertical transverse sectional view of an apparatus in which the central portion of the roof is formed by a single metal diaphragm

of the kind used to form the conventional breather roof.

Figure 5 is a vertical transverse sectional view, illustrating the principle of operation of the apparatus shown in Figures 1 and 2; and

Figure 6 is a vertical transverse sectional view, illustrating how the apparatus shown in Figures 1 and 2 can be equipped with a means for conducting rain water directly off of the central portion of the roof, and for preventing rain water on the peripheral portion from backing up onto the central portion of the roof.

In the apparatus shown in Figures 1, 2 and 5, A designates the side wall of the tank or container, B designates the central portion of the roof which is constructed in the form of a cone-shaped or convexed member, C designates the flexible peripheral portion of the roof that surrounds said central portion or lies in a vertical plane that is beyond or outside of the vertical plane in which the central portion B is disposed, said peripheral portion having its outer edge attached in a gas-tight manner to the side wall A, and projecting inwardly from said side wall, and D designates the rim whose opposite ends are attached in a gas-tight manner to the outer edge of the central portion B and to the inner edge of the flexible peripheral portion C. The rim D, which is of stiff construction, is herein illustrated as being formed by a relatively heavy, cylindrical-shaped member, disposed vertically and connected by gas and liquid-tight joints to the two portions B and C. Said parts B, C and D are so proportioned and combined, that when the roof is in its extreme downwardly flexed condition, as shown in solid lines in Figure 2, the top edge of the rim D is located in a horizontal plane that is either coincident with or slightly above the horizontal plane in which the top edge 40 of the tank side wall A lies. In the particular form of my invention herein shown, the radius of the flexible peripheral portion C is only a fractional part of the radius of the entire roof. When the internal pressure of the gas space of 45 the tank is not great enough to raise the roof or flex it upwardly, the flexible peripheral portion C slopes downwardly and inwardly, at a sharp pitch, from the peripheral edge of the roof, thus forming a water collection trough or valley x at the point where said peripheral portion joins or merges into the rim D. In this position of the roof it is impossible for rain water in the trough x to back up onto the central portion B of the roof, due, of course, to the fact that the top edge of the rim D is higher than the level of 50 any load of water that can collect in and remain in said trough, even though the drain outlet at the lower end of said trough becomes clogged.

When the roof moves upwardly into its extreme elevated position, the peripheral portion C assumes such a shape or form that any water thereon which fails to escape through the drain 55 I, will be discharged radially at the peripheral edge of said portion C. At all times, i. e., when the roof is in its extreme downwardly flexed position, or extreme elevated position, or while the roof is passing from one extreme position to the other, the central portion B of the roof remains in such a shape or form that rain water will drain off of same, rapidly and efficiently, onto the peripheral portion C.

When the roof is in its downwardly flexed position, it is sustained by a supporting structure that may be made of considerably less area and load-carrying capacity than the supporting structure

of the conventional breather type roof, due to the fact that my improved roof is of such design that no relatively great load of rain water can collect and remain on the roof. Preferably, said roof-supporting structure is so made that after the roof plates have been welded together and combined with the rim D, said supporting structure can be modified or adjusted in a way that stretches the roof plates and causes the two portions B and C of the roof to assume a shape or form that adds considerably to the storage capacity of the apparatus without increasing the size of the apparatus or the cost of building the roof. In the form of my invention shown in Figures 1 and 2, the roof supporting structure comprises permanent frame members consisting of uprights 2, circumferentially-disposed beams 3 sustained by said uprights, radially-disposed rafters 4 extending inwardly from the side wall of the tank and supported at their inner ends by the beams carried by one circular row of uprights 2, and a second set of rafters 5 extending radially from a center upright and supported at their outer ends by the beams 3 carried by the second circular row of uprights 2. Said supporting structure also comprises temporary frame members consisting of removable blocks 6 positioned under the lower ends of the uprights 2, and a set of removable, radially-disposed rafters 7 supported by the two sets of circumferentially-disposed beams 3, said rafters 7 being shown in broken lines in Figure 1, so as to indicate that they are removable. In constructing the roof, the roof plates are first laid on the rafters 4, 5 and 7, and welded together while the blocks 6 are positioned under the uprights 2. Thereafter, the blocks 6 and the rafters 7 are removed, thus causing the two portions B and C of the roof to assume a sharper downward pitch or angle. This downward movement or deflection of the portions B and C causes the metal plates from which said portions are constructed to be stretched, with the result that the area of the roof is increased by the stretching of the roof plates, and any slight wrinkles in said plates are removed. Increasing the area of the roof by such stretching of the roof plates, coupled with the sharp downward pitch of the flexible portion of the roof, increases the storage capacity of the apparatus, without adding to the cost of the roof, and removing wrinkles from the roof plates, eliminates uneven surfaces on the top side of the roof that might tend to cause rain water to form puddles on the roof, or not flow freely over the roof. I have found that a supporting structure of the kind above described forms an adequate support for the roof when it is in its downwardly-deflected position, notwithstanding the fact that said supporting structure comprises fewer frame members, and frame members of considerably less weight than those used in the supporting structure of the conventional breather type roof, this being made possible, as previously stated, because the shape or form of the roof and the way in which the two portions B and C of same are combined with the rim D, precludes the possibility of an abnormally large or heavy load of rain water ever collecting and remaining on the roof.

During the upward and downward movement of the roof, the flexing of the roof plates is controlled in such a way that the roof is practically noiseless in operation, and wrinkles do not form in the roof plates to retard or interfere with the drainage of rain water. These highly desirable

results are attained by incorporating the stiff, heavy rim D in the roof and arranging a weight or load E eccentrically on the central portion B of the roof, at one side of the edge of said portion, as shown in Figure 1. The combination of said heavy rim and eccentric load also insures rapid and efficient discharge of rain water through the drain 1 that leads from the water collection trough or valley x. If the plates constituting the two portions B and C of the roof are of the same thickness, then the area B of the roof inside the rim D is, on the average, heavier than the flexible peripheral area or portion C. As pressure in the gas space rises, then the first movement is in the portion C. Said portion C will flex upwardly all around (as shown on the left hand side of Figure 5), before the rim D leaves the roof supporting structure at any point. The rim D constitutes a very heavy weight—about 5 to 10% of the weight of the entire roof plates. Thus, as the peripheral portion C rises, it is flexed up as an entirety throughout its entire area, before its inner periphery or edge portion moves upwardly bodily. As a result of this action, the peripheral portion of the roof rises noiselessly and without forming wrinkles of the kind that always form in the peripheral portion of the conventional breather roof, during vertical movement of the roof in either direction. As the pressure continues to increase, the rim D begins to rise, but it assumes a tilted or angular position, due to the weight imposed on the outer edge of the central portion B of the roof by the eccentric load E. In other words, the weight or load E holds down one side of the rim D, while upward pressure is being exerted on the other side of the rim. In addition to controlling the flexing of the roof, as hereinafter explained, this tilting action of the rim imparts a slight circumferential pitch to the trough or gutter x, in a direction that insures any small puddles of rain water in said gutter flowing to the drain 1 leading from said gutter. A further increase in the internal pressure of the gas space, causes the rim D to move bodily in an upward direction, the rim remaining in its tilted or angular position, until the high side of the annular peripheral portion C of the roof gets tight enough to hold back said high side. Thereafter, the low side of the peripheral portion of the roof rises faster than the high side, and the rim gradually assumes a level or horizontal position as the roof reaches its extreme upwardly flexed position. However, the high side of the rim passes through the horizontal plane in which the top edge of the tank side wall A lies, before the low side of the rim reaches said horizontal plane. The inner edge of the flexible annular portion C of the roof is thus eased up through the intermediate horizontal plane lying between the two extreme positions of the flexible portion C of the roof, noiselessly and with a minimum of stress. During the downward movement of the roof, the inner edge of the flexible portion C is eased down through the intermediate horizontal plane in a similar manner, the stiff rim D causing the peripheral portion of the roof to rise and fall in a plane, during the upward and downward movement of the roof.

In the form of my invention illustrated in Figure 3, the central portion of the roof carried by the rim D is formed by a flexible diaphragm 8, whose outer edge is attached by a collar or ring-shaped connecting device 8^a to an annular flexible member 8^b that is fastened to the top edge of the rim D, the diaphragm 8 being provided

adjacent its outer edge with an eccentrically-disposed weight or load E', and the annular flexible part 3^b being provided with an eccentrically-disposed load E. In a roof of this particular construction, the flexible center diaphragm 8 will flex upwardly first, because that is the portion of the roof having the lowest average weight. Next, the collar or ring-shaped connecting device 8^a will move upwardly, and finally, the rim D will rise. This method of constructing the central portion of the roof gives a considerable increase in available volume change, at a very little expense of increase in water load. The flexible annular part 3^b and the collar 8^a will operate just as if the outer edge of said part 3^b were attached to the top edge of the tank side wall. In other words, the rim D acts as a "wrinkle stop," as compared to the conventional breather roof. If as much slope were put into a conventional breather roof as the accumulated slope in the peripheral portion C, plus portion 3^b, plus diaphragm 8, the accumulation of wrinkles necessary to pass the entire roof up through a horizontal plane would be so great that the plates or welded joints of the roof would crack. But each of the parts C, 3^b and 8 of the roof operate entirely independently of each other, as far as their own flexing is concerned.

In the form of my invention shown in Figure 4, the central portion of the roof is formed by a conventional breather roof diaphragm 9, provided adjacent its outer edge with an eccentrically-disposed weight or load E. From the previous description of my invention the operation of the roof shown in Figure 4 will be obvious.

Figure 6 illustrates a feature that may be incorporated in a roof of the kind shown in Figures 1 and 2. Said feature consists of a means for conducting rain water off the central portion of the roof, without the necessity of said water first draining onto the flexible peripheral portion of the roof, and means for preventing rain from backing up on the peripheral portion C and flowing onto the central portion B of the roof, in the event the outer edge of the central portion of the roof ever reaches a position lower than the top end of the tank side wall. As shown in said Figure 6, the rim D is extended upwardly above the outer edge of the central portion B, so as to form a baffle or water trap 10 that prevents a load of rain water in the gutter or valley x from ever backing up onto the portion B. A drain 11 leads outwardly from the inner side of the baffle 10, so as to discharge rain water directly from the portion B, over the top edge of the side wall of the tank.

Having thus described my invention, what I claim as new and desire to secure by Letters Patent is:

1. A breather type roof for storage tanks, comprising a central portion of less radius than the tank side wall and a flexible peripheral portion of substantially annular form arranged beyond or outside of said central portion, said peripheral portion having its outer edge attached to the top edge of the tank side wall, and an annular rim of substantial weight, extending continuously around the roof and attached to the outer edge of said central portion and to the inner edge of said peripheral portion so as to impose a downward force or load on the inner edge of said peripheral portion, that tends to prevent said inner edge from rising or moving upwardly bodily, until after said peripheral portion has been placed under considerable tension by

the pressure of the gases confined in the tank.

2. A tank roof of the kind described in claim 1, which also includes a means for causing the central portion of the roof and said rim to tilt during the bodily upward movement of the inner edge part of the peripheral portion of the roof.

3. A storage apparatus, comprising a container or tank, and a breather type roof connected to the tank side wall by a gas and liquid-tight joint, and composed of a peripheral portion that is capable of flexing upwardly and downwardly through a horizontal plane, a center portion lying in a different vertical plane than said peripheral portion and constituting a large portion of the area of the roof, said center portion being of less diameter than the side wall of the tank, and a substantially annular-shaped, eccentrically-loaded rim, attached to the inner edge of said peripheral portion and to the outer edge of said center portion and disposed so as to always maintain the outer edge of said center portion in a higher horizontal plane than the inner edge of said peripheral portion so that water that may collect on said peripheral portion is prevented from flowing onto said central portion, said eccentrically-loaded rim being so constructed and arranged that said central portion and said rim will tilt during the upward movement of the inner edge part of said peripheral portion.

4. An apparatus of the kind described in claim 3, in which the top edge of said rim when the roof is in its downwardly-flexed position, is located in a horizontal plane coincident with or higher than the horizontal plane in which the top edge of the tank side wall lies.

5. An apparatus of the kind described in claim 3, in which the center portion of the roof is cone-shaped or convex-shaped, in any and all positions of the roof.

6. An apparatus of the kind described in claim 3, in which the center portion of the roof is formed by a metal diaphragm that is capable of flexing upwardly and downwardly.

7. An apparatus of the kind described in claim 3, in which the center portion of the roof is formed by a plurality of concentrically-arranged, flexible parts and an interposed ring-shaped connecting device that maintains adjacent edges of said concentrically-arranged parts in different horizontal planes.

8. A storage apparatus, comprising a tank, a breather type roof, comprising a flexible, washer-shaped, peripheral portion having its outer edge attached in a gas-tight manner to the side wall of the tank and projecting inwardly from said side wall, a center portion of relatively great radius but of considerably less diameter than the side wall of the tank, disposed in a different vertical plane than said peripheral portion, an interposed, vertically-disposed, cylindrical-shaped rim of stiff construction attached in a gas-tight manner to the inner edge of said peripheral portion and to the outer edge of said center portion and extending continuously around the roof, so as to maintain the center portion in a higher horizontal plane than the peripheral portion and prevent water from flowing from said peripheral portion onto said center portion, and means for causing said rim and center portion to tilt during the upward movement of the inner edge of said peripheral portion during the vertical movement of the roof.

9. A storage apparatus, comprising a tank, a breather type roof, comprising a flexible, wash-

er-shaped, peripheral portion having its outer edge attached in a gas-tight manner to the side wall of the tank and projecting inwardly from said side wall, a center portion of relatively great radius but of considerably less diameter than the side wall of the tank, disposed in a different vertical plane than said peripheral portion, and an interposed, vertically-disposed, cylindrical-shaped rim of stiff construction attached in a gas-tight manner to the inner edge of said peripheral portion and to the outer edge of said center portion and extending continuously around the roof, so as to maintain the center portion in a higher horizontal plane than the peripheral portion and prevent water from flowing from said peripheral portion onto said center portion, said rim being relatively heavy and the center portion of the roof being provided with an eccentrically-disposed load so as to cause said center portion and rim to tilt during the upward movement of the inner edge part of said peripheral portion.

10. A storage apparatus, comprising a tank, a breather type roof, comprising a flexible, washer-shaped, peripheral portion having its outer edge attached in a gas-tight manner to the side wall of the tank and projecting inwardly from

said side wall, a center portion of relatively great radius but of considerably less diameter than the side wall of the tank, disposed in a different vertical plane than said peripheral portion, an interposed, vertically-disposed, cylindrical-shaped rim of stiff construction attached in a gas-tight manner to the inner edge of said peripheral portion and to the outer edge of said center portion and extending continuously around the roof, so as to maintain the center portion in a higher horizontal plane than the peripheral portion and prevent water from flowing from said peripheral portion onto said center portion, and means for causing said rim and center portion to tilt during the upward movement of the inner edge of said peripheral portion during the vertical movement of the roof, said center portion comprising the following elements, to wit: (1) a central disk; (2) a substantially horizontally-disposed, washer-shaped part arranged in concentric relation with said disk in a different horizontal plane; and (3) a vertically-disposed, tubular member attached to the outer edge of said central disk and to the inner edge of said washer-shaped part.

JOHN H. WIGGINS.
